UNITED STATES PATENT OFFICE.

CLARENCE EMERSON POSTON, OF CRAWFORDSVILLE, INDIANA.

BRICK-MACHINE.

No. 826,356.

Specification of Letters Patent.

Patented July 17, 1906.

Application filed February 16, 1906. Serial No. 301,372.

To all whom it may concern:

Be it known that I, CLARENCE EMERSON POSTON, a citizen of the United States, residing at Crawfordsville, in the county of Montgomery and State of Indiana, have invented a new and useful Improvement in Brick-Machines, of which the following is a specification.

This invention relates to brick-machines, and has for its object to provide means for giving to the bricks produced by the machine unique and novel faces and ends as distinguished from known smooth or glazed faces. Rough-surfacing is desirable for a variety of reasons, among which are more ornamental appearance and a better bond when laid, and this invention provides means for producing it without hand-labor and the use of "brooms" or other devices heretofore employed for that purpose.

The device herein disclosed embodies the use of wires applied to the mouth or delivery-opening of a brick-machine which delivers therefrom a continuous bar or strip of clay, which is taken to the cutting-table to be cut into bricks of desired size. These wires roughen the sides or surface of the bar, so that when the bricks are finally cut and fired the desirable rough surface is produced as distinguished from the smooth surface which would otherwise result.

A further feature of my invention is the use of scrapers which scrape off and cast aside the strips cut by the wires from the sides of the bar, which form the ends of the finished bricks.

A further feature of this invention is a wire provided with disks attached near the top of the mouthpiece to loosen and cut into fragments or make ragged the top of the bar to prepare the bricks with rough faces and ends. The top of the bar makes the face of the brick in this case, and a plain wire would not do, because it would shave off the waste, but not break it, and it would lie up and cover the roughened surface, inasmuch as there is no practicable way of sweeping or cleaning the waste off of the top of a bar of clay. The wire with disks cuts the waste and breaks it into fragments, giving the desired surface effect, and also small enough so that when a roller is subsequently passed over the surface

the fragments unite with the bar and form a good bond, still showing the rough surface.

The invention is illustrated in the accompanying drawings, in which—

Figure 1 is a perspective view of the mouthpiece of a brick-machine provided with the improvement. Fig. 2 is a horizontal section thereof. Fig. 3 is a perspective of a modification in which the disk-wire is omitted and a middle plain wire is used to divide the bar, forming two rough-surface bricks in each length; and Fig. 4, a detail of wire, showing square plates set at a right angle. Figs. 5, 6, and 7 are detail perspective views of the several parts detached.

Referring specifically to the drawings, 6 indicates the mouthpiece of the brick-machine. This has near the sides thereof vertical wires 7, which shave off thin strips from the edges of the bar of clay as it issues from the mouth. These wires are strained over the rim of the mouthpiece and secured at the ends by means of hooks 8, projecting from plates 9, attached to the walls of the mouthpiece by means of screws 10. The screws are left loose when the wires are first attached, and as the wires stretch the screws are tightened to take up the slack.

At 11 are indicated scrapers, which consist of metal strips secured at their upper ends to the top of the mouthpiece and depend in line with the wires 7, being twisted to present their edges to the cut produced by the wires and to throw off to the sides the waste strips cut off by the wires.

In the form shown in Fig. 1 a top wire 12 is used, fastened at the ends by means of screw-hooks 17, secured to brackets 18, attached to the outside of the mouthpiece, and these wires carry disks 13 of thin metal, set slantingly or at an angle to the line of motion of the bar, and the inclination of the alternate disks is reversed. The wire is so positioned that the disks cut into or score the top of the bar. To prevent sag of this wire, inasmuch as the strain is great, it is supported at the middle by a screw 14, having a notch in the end, which holds the wire, the screw being held by a plate 15, attached to the top of the mouthpiece. Instead of being set round and slantingly the disks may be square and at right angle to the wire, as shown in Fig. 4,

and large or small, as desired, all depending on the plasticity or resistance of the clay.

The form shown in Fig. 3 is used for thin bricks to divide the bar in half. A horizontal wire 16 is placed across the middle of the mouth and secured at the ends by the same means. The wire produces the rough surface, and during the subsequent operations the upper and lower halves remain together and are handled as one brick until after firing, when they are separated.

It will be understood that after the bar is cut in the manner indicated it is cut vertically and transversely into bricks on an ordinary cutting-table. The face and also the ends of the brick are rough-surfaced by the means indicated. The scrapers 11 prevent the shavings or strips adhering to and being carried along with the bar, which would obstruct other parts of the machinery and prove generally inconvenient, and effectively dispose of the waste.

It will be understood that my invention will be found useful in rough-surfacing hollow building-blocks, as well as bricks proper, and in referring to "bricks" and "brick-machines" in the foregoing specification and the appended claims I desire it understood that I include in said terms hollow building-blocks and machines for making the same, as well as bricks proper and machines for making the same.

Having thus described my invention, what I claim as new, and desire to secure by Letters Patent, is—

35

1. The combination with the mouthpiece of a brick-machine, of wires stretched across the same, at the sides thereof, for shaving strips from the bar, and scrapers beyond the wires, adapted to cast off the shavings so produced.

2. The combination with the mouthpiece of a brick-machine, delivering a bar of material, of a wire stretched across the same, adjacent to the surface of the bar, and having thereon cutting devices adapted to cut into the surface of the bar.

3. The combination with the mouthpiece of a brick-machine, delivering a bar of material, of a wire stretched across the same, adjacent to the edge of the mouth, and having thereon disks arranged at an angle to the line of motion of the bar and adapted to break the surface of said bar.

4. The combination with the mouthpiece of a brick-machine, delivering a bar of material, of means to shave strips from the surfaces of the bar, and scrapers beyond said means, arranged to cast off the said strips from the bar.

CLARENCE EMERSON POSTON.
